JOSEPH GARAMI, OF NEWARK, NEW JERSEY, AND MAX FODOR, OF NEW YORK, N. Y.

COMBINATION-DOLL.

1,325,986.

Specification of Letters Patent. Patented Dec. 23, 1919.

Application filed December 2, 1918. Serial No. 264,994.

To all whom it may concern:

Be it known that we, JOSEPH GARAMI and MAX FODOR, citizens of Hungary, and residents, respectively, of Newark, in the county 5 of Essex and State of New Jersey, and New York, in the county of New York and State of New York, have invented new and useful Improvements in Combination-Dolls, of which the following is a specification.

10 This invention relates to dolls, the invention being more particularly related to improvements in dolls of the combination type, having coöperating movable elements.

A main object of the invention is the provision of a doll having movable arm elements, movable eye elements, a movable chin element, and having associated mechanism by which, whenever either the arm elements or the doll body are moved in respect to each 20 other, the eye elements and the chin element will be caused to move or oscillate automatically.

Another object of the invention is the provision of a rocking doll embodying the foregoing elements, arranged in such manner that when the doll is rocked, the chin element will be oscillated to produce the effect of an open and closed mouth, and the eye elements will be oscillated to produce the 30 effect of open and closed eyes.

With the foregoing and other objects in view, the invention resides in the details of construction and in the arrangement and combination of parts hereinafter described, 35 defined in the claims, and illustrated in the accompanying drawings, forming a material part of this specification; and in which:—

Figure 1 is a view in side elevation of a 40 rocking doll made in accordance with our invention, parts being broken away and parts being shown in section.

Fig. 2 is a view in perspective of a section of the head and shoulders of the structure, showing in particular the working 45 parts therein arranged.

Fig. 3 is a view in elevation of the front longitudinal half of the doll, the same being shown as it appears from the rear side thereof.

50 Fig. 4 is a partial sectional view of the head, showing the relative positions of the working parts when the mouth is about to be opened and the eyes about to be closed.

Fig. 5 is a view in front elevation of the head.

In the embodiment of the invention herein presented, the doll is cast in two longitudinal shell-like halves or sections 10 and 11, respectively, the former denoting the front half of the structure and the latter the rear half thereof. With each half or section is also cast a part of the base 12, which in form is like the segment of a cylinder, although its rocking surface 13 should, obviously, be made on an arc considerably 65 greater than an arc of a true circle. Transverse the direction of rocking movement, the base parts are each cast with a solid or weighted portion 14 located in such position that when the sections are united, the doll 70 structure will be maintained normally in upright or vertical position, as illustrated in Fig. 1. The sections are united by gluing or otherwise securing them together; and they are preferably cast or formed from a 75 composition of matter which, while comparatively light, is substantially unbreakable under ordinary use.

The head portion 15 of the front section 80 10 is preferably cast in the specific form shown in Fig. 2, and in the shoulder regions with the rearwardly projecting lugs 16. Mounted for rotation in these lugs is a shaft 17, the extremities of which extend exteriorly of the lugs and to which are rigidly 85 secured the arm elements 18 and 19. These arms are preferably cast as solid elements; and in each hand is cast or secured a weight as 20, so that when the doll structure is rocked upon its curved base, the arm elements, continuing to fall in a vertical direction, will impel the turning of the 90 shaft 17.

Between the shoulder lugs 16, a plate 21 is secured, midway its length, upon the shaft 95 17 so as to turn therewith, and the extremities thereof are bent upwardly upon themselves to provide the contacts 22 and 23. The head portion 15 is cast on each side of the nose 24 with the usual eye sockets 25; 100 and below the nose with an upper lip protuberance 26, below which is a chin opening 27. Connecting the cheek walls behind this chin opening 27 is a fixed shaft 28. Eccentrically mounted on this shaft for turning 105 movement is an actuating plate 29, which is

5 stamped or otherwise formed out of a piece of thin sheet metal so as to have an inclined portion 30 connecting the horizontal portions 31 and 32. The horizontal portion 32 at its outer end is formed with offset lugs 33, so that when the said portion 32 is bent underneath upon itself as at 34, the lugs 33 may be turned upwardly and folded or crimped upon the said portion 32

10 In Fig. 2, it will be seen that the shaft 28 extends through the lugs 33 and that the arrangement is such that when the doll structure is in vertical position, the horizontal portion 31 will lie flat upon the contacts 22 and 23, maintaining a chin piece 35, carried by the curved portion 34, snugly fitted in the chin opening 27. The chin piece 35 includes a lower lip 36, which when the chin piece is thus maintained in the 15 opening 27, is held in such close proximity to the upper lip 26 that the mouth of the doll will appear as approximately closed. As a means of positively holding the parts in these relative positions, a weight 37 is secured upon the free end of the horizontal plate 31.

18 Formed with the inclined plate 30 is a lug 38 providing an eye 39, in which is engaged a U-shaped link 40, whose free limb extremities 41 and 42 are pivotally engaged with the rearwardly projecting outer lugs 43 of the eye shells 44 and 45, respectively. Extending through the outer lugs 43 as well as through the inner lugs 46 of said eye shells, is a shaft 47, whereby the eye shells are mounted for oscillating movement. Said shaft 47 is supported in a bridge 48, secured in such position on the inner side of the head, immediately behind the nose 24, that the said eye shells 44 and 45 are operatively maintained in the sockets 25. This whole arrangement is such that when the chin piece 35 is maintained in the position just described, wherein the lips are in 29 such close proximity as to produce the effect of an approximately closed mouth, the iris regions 49 will be visualized centrally through the eye-sockets 25, as best seen in Fig. 5.

30 When the doll rocks forwardly, the contact 22 engages the forward end of the horizontal portion 31, tilting the actuating plate 29 upon its axis so as to swing the jaw 35 downwardly opening the mouth. Simultaneously with this movement, the eye-shells are tilted downwardly so as to give the appearance of closed eyes. When the structure rocks rearwardly a short distance beyond vertical position, the mouth is opened 35 and the eyes closed in a similar manner, the operation this time, however, being accomplished through the engagement of the contact 23 with the rear end of the horizontal plate 31. Thus, each time the doll rocks 40 a short distance from vertical position either

forwardly or rearwardly, the chin element and the eye elements will be oscillated simultaneously. By moving either one of the arms 18 or 19, either forwardly or rearwardly, the same results are also obtained 70 in an obvious manner.

75 It will be understood that while we have shown the preferred form of our invention, we do not want to be limited to its precise mechanical or other details, and may resort to such alterations and modifications as come within the scope of the claims hereunto annexed.

Having thus described our invention, what we claim is:—

80 1. In a doll, the combination with the body thereof, of eye elements adapted to be oscillated, a chin element adapted to be oscillated, a connection for oscillating the eye elements from the chin element, connected 85 arm elements movable together in respect to the body, and means whereby either movement of the arms with respect to the body or movement of the body with respect to the arms will effect the oscillation of said 90 chin element.

95 2. In combination with a doll of the kind having oscillatable eye elements and movable arm elements, a shaft movable with the arm elements, a plate movable with said shaft and provided with contact extremities, a chin element supported for movement to give the effect of an open or closed mouth, a link forming a connection between said chin element and the said eye elements, and 100 means engageable with said contact extremities upon the movement of the arms whereby to effect simultaneously the oscillation of said chin element and said eye elements.

105 3. In a doll having a body including a rocking base, pivoted eye elements adapted to oscillate to give the effect of open or closed eyes, a pivoted chin element adapted to oscillate to give the effect of open or closed mouth, and means rendered operative through the rocking of the body upon its base whereby simultaneously to produce the oscillation of said eye elements and said chin element.

110 4. In a doll having a body including a rocking base, eye elements pivoted for oscillation to give the effect of open or closed eyes, a chin element pivoted for oscillation to give the effect of an open or closed mouth, arm elements having movement in respect 115 to the body, and means controlled by the arm elements and rendered effective on the rocking of the body upon its base whereby to produce the simultaneous oscillation of said eye elements and said chin element.

120 5. In a doll, the combination with movable eye elements and a movable chin element, of arms having movement independent of the movement of the body of the doll, means whereby movement of the chin element is 125 130

communicated to the eye elements, a connection between and movable with the arms, a contact plate movable with said connection, and means carried by the chin element in 5 position to be impinged by said contact plate whereby on the movement of arms in respect to the body or on the movement of

the body in respect to the arms, the said eye elements and said chin element will be caused to oscillate simultaneously.

In testimony whereof we have signed our names to this specification.

JOSEPH GARAMI.
MAX FODOR.
